UNITED STATES PATENT OFFICE.

GEORGE P. PIERCE, OF KANSAS CITY, MISSOURI.

SILO-REINFORCING-ROD ANCHOR.

1,368,653.

Specification of Letters Patent. Patented Feb. 15, 1921.

Original application filed May 22, 1917, Serial No. 170,297. Divided and this application filed September 6, 1918. Serial No. 252,811.

To all whom it may concern:

Be it known that I, GEORGE P. PIERCE, a citizen of the United States, residing at Kansas City, in the county of Jackson and 5 State of Missouri, have invented certain new and useful Improvements in Silo-Reinforcing-Rod Anchors, (division of my application Serial Number 170,297,) of which the following is a specification.

10 This invention relates to silo reinforcing rod anchors and is a division of my application Serial Number 170,297 filed May 22, 1917. The present structure is designed for use in connection with a door frame suitably mounted within the silo structure itself and coöperative with the circumferential reinforcing rods to give a suitable anchorage at the ends of the latter to avoid passage over or through the door openings.

20 Particularly in cement block silo construction, the thicknesses of the various mortar joints may vary and, in this latter construction, the circumferential reinforcing rods are usually embedded between two 25 horizontal roadways of blocks. It is essential that suitable anchors be carried by the door frame for securing the ends of these rods but their exact location can not be predetermined because of the variations in 30 thicknesses of mortar joints as outlined above and also due to the various distortions and shrinkages of the cement blocks themselves. For this reason, the main object of the present invention resides in a 35 structure of anchor particularly adapted for the reception of the ends of these reinforcing rods and which may be so positioned and associated with the door frame that the various inequalities and distortions met 40 with in actual practice may be handily overcome. To this end, the anchor is of a peculiar form so mounted upon the door frame as to permit of its proper adjustment and also constructed to accommodate 45 lateral adjustable connection of the reinforcing rod ends.

The structure for accomplishing the foregoing is shown in the accompanying sheet of drawings which represents the preferred 50 embodiment of my invention. In these drawings, similar characters of reference designate corresponding parts throughout and,

55 Figure 1 represents the partial face view of a cement block silo with the door frame

in its applied position, a portion of the frame and block structure being broken away to clearly disclose the anchorage for one end of a circumferential reinforcing rod, and

60 Fig. 2 is a fragmentary view in perspective showing the anchor attached to the door frame and illustrating the reinforcing rod in broken lines.

In Fig. 1, the silo is shown as being built 65 up of a plurality of blocks 1, the mortar joints being shown by single lines designated 2. While the present invention is shown in conjunction with cement blocks, it is not particularly limited to such application but is equally applicable wherever the 70 types of adjustments already described are essential providing the reinforcing rods may be adapted to that particular type of structure.

75 The door frame is designated in its entirety by the reference numeral 3 and its top and bottom and vertical edges are preferably in the form of channels as illustrated in Fig. 2 to embrace the silo structure surrounding 80 the door opening. The door frame is closed by means of the door 4, the latter being drawn into proper holding position and latched in such position by means of the latching structures designated generally by 85 the reference numerals 5 and 6 all as described and claimed in my application above referred to.

90 Between the inner and outer legs 7 and 8 respectively of the vertical portions of the door frame there are located the desired number of anchors for the circumferential reinforcing rods 9, each of these anchors consists preferably of an angularly shaped member whose vertical leg is designated 10 95 and whose horizontal leg is designated 11. The vertical leg is provided with a vertically disposed slot 12 and is attached to the door frame by means of the bolt and nut structure 13. A slot 12 in the vertical leg 10 100 of each member is made of a height to permit of the normal variations in the thicknesses of mortar joints by various workmen. It will be understood that should the thicknesses of these mortar joints vary, for instance, from the bottom of the door frame to the top of the frame, the reinforcing rod at the top would be located a greater distance away from the lower one than it should be and than could be accommodated 105 110

unless suitable adjustments are provided. For this reason, either the upper anchors 5 may be properly adjusted or the door frame may be moved slightly vertically but permitting the lower anchors to remain in position and the entire structure then drawn tight and in rigid holding relation. Each of these reinforcing rods have their ends turned down at right angles as is illustrated 10 at 14 and these ends are adapted to fit in slots 15 in the horizontal legs 11 of the anchors. This permits of the necessary lateral adjustment of the reinforcing rod ends as may be encountered in the field. 15 From the foregoing description, taken in connection with the accompanying sheet of drawings it will be apparent that I have provided a structure which permits the rapid 20 association of circumferential reinforcing rods and the door frames. As stated, these clips merely form anchors for the ends of the reinforcing rods to avoid passage over the door opening, the door frames themselves functioning as continuations of the 25 reinforcing rods. The proper adjustments

such as may be caused by mortar joints of varying thicknesses and distortions to be found in the blocks from which the silos are made may be readily accomplished. At the same time the door frame structure may 30 be initially equipped with these anchors and shipped in connection therewith.

What I claim is:

In a silo, a door frame, a reinforcing rod extending around the silo, angle members 35 carried by the vertical sides of said frame between its inner and outer edges, one leg of each member lying flat against that portion of the frame between its vertical sides and being provided with a vertical slot, and means for adjustably securing said members to said frame by said slots, the other leg of each member being disposed crosswise between the sides of said frame and being provided with a slot extending crosswise between the frame sides for the reception of 40 one of said rod ends.

In testimony whereof I affix my signature.

GEORGE P. PIERCE.
